UNITED STATES PATENT OFFICE

EDWARD F. GRAF, OF GRAND RAPIDS, MICHIGAN, ASSIGNOR TO WINTERS & CRAMPTON MFG. CO., OF GRAND RAPIDS, MICHIGAN, A CORPORATION OF MICHIGAN

LATCH

Application filed April 15, 1929. Serial No. 355,120.

This invention relates to a latch construction particularly adapted for refrigerators though in no sense limited in use thereto. It is a primary object and purpose of the present invention to provide a latch structure which is reversible in use, that is, one which may be applied to either doors swinging to the right or to the left, the change in adapting the latch for use on one type of door to 10 the other being a very simple one and one which requires no variation whatever in the manufacturing process of the parts which are assembled to make the latch.

A further object of the invention is to provide a latch in which when the latch lever thereof is manually disengaged from the keeper it is held in a position such that the keeper engaging end of the latch lever passes above the keeper hook and is entered back 20 of said keeper hook automatically as the door is finally closed through a cam operation upon the latch lever which swings the same from its keeper disengaged position to a point where a spring means, which previously 25 has acted to hold the lever in keeper disengaged position, is caused to act to force the latch lever into wedging engagement with the keeper hook.

An understanding of the invention and the 30 constructions embodying the same may be had from the following description taken in connection with the accompanying drawings in which,

Fig. 1 shows a front and a side elevation 35 of the latch structure applied to a door and door jamb with the lever in the position it occupies when it is disengaged from the keeper on opening the door, the housing for the latch lever mechanism being shown in section.

Fig. 2 is a like front and side elevation illustrating the latch lever engaged with the keeper.

Fig. 3 is a view similar to the front elevation shown in Fig. 1, showing the latch applied to a door which swings in a direction opposite to that shown in Fig. 1.

Fig. 4 is a transverse section through latch structure applied to the door.

Fig. 5 is a longitudinal section through said latch structure.

Fig. 6 is a bottom elevation of the latch construction.

Fig. 7 is a fragmentary enlarged constructive detail in elevation and vertical section showing the assembly of the spring control means of the latch construction with the latch lever and the housing or casing therefor, and

Fig. 8 is a view similar to that shown in Fig. 7 illustrating a slight change and addition to the construction shown in Fig. 7.

Like reference characters refer to like parts in different figures of the drawings.

In the construction shown, the latch lever assembly is secured to the face of a door 1 near the free vertical edge thereof. Said construction includes housing 2 of sheet metal which has a top and inwardly extending sides and ends with ears 3 turned outwardly from the inner edge portions of each side of the housing through which screws or equivalent fastening devices pass to secure the casing to the door. Openings 4 and 5 are made through the opposite ends of the latch housing and a bottom plate 6 closes the lower side of the housing, said plate being a plate of flat metal in which two tongues 7, as shown in Fig. 6, are provided located symmetrically with respect to a plane through the pivot of the latch lever, hereafter described, and disposed midway between the opposite upper and lower sides of said housing. The use of the tongues 7 will appear later with reference to the latch lever.

The latch lever 8 extends through the housing, passing through said openings 4 and 5 and at one end is formed into an operating handle 9. The other end 10 may directly engage with the keeper hook or a keeper hook engaging roller 11 may be mounted thereon.

The lever 8 is formed from flat metal and shaped so that the intermediate portion thereof within the housing is of channel form, having an upper web and inwardly extending spaced apart flanges 12. Within the housing an elongated opening 13 is cut through the web described and at the end thereof, adjacent the pivot, the opening is formed with two concaved seats 14 separated

by a central projection 15, as shown. The pivot pin 16 is a sleeve which passes through the bottom 6 and is received at its upper or outer end in a bearing 17 which, preferably, is formed in the metal of the housing 5 placed when the opening 4 is made at one side of the housing, said metal being turned inwardly and having the bearing 17 formed therein, as shown in Fig. 5. The lower end of the pivot sleeve 16 is spun outwardly 10 against the under side of the base plate 6, as indicated at 16^a (Figs. 5 and 6), thereby serving to connect and secure the pivot sleeve in place.

15 A bar 18 is formed at one end with a right angularly extended head 19, the bar being located within the housing between the outer side of the housing and the upper or outer side of the latch lever. The head 19 extends into the opening 13 and seats 14 described.

20 A coiled spring 20 is located around the bar 18, pressing against the head 19 at one end and at the opposite end bearing against an end of the housing above the opening 5. Said housing is formed with an inwardly 25 pressed projection 21 as a locating and holding means for the end of the spring.

The latch lever assembly described is one in which, when the lever is turned to the position shown in Fig. 1, the line of force of the spring 20 passes slightly above the axis of the pivot 16 and serves to hold the lever yieldingly in the position there shown. But on turning the lever about its pivot, the line of force of the spring passes across the axis 30 of the pivot 16 to below such axis and thereupon acts to turn the lever in the opposite direction. When the construction is to be used on a door swinging to the right, as shown in Fig. 1, the head 19 is seated in one 35 of the seats 14 and one of the tongues 7, is pressed inwardly into the housing as shown in Fig. 4 to serve as a limit stop for the lever. When the construction is to be used on a 40 door swinging to the left, as illustrated in Fig. 3, the head 19 is seated in the other seat 14 and the tongue 7 which is bent inwardly is the opposite tongue 7, though it will be at the lower side of the lever.

45 The keeper hook which is to be attached to the door jamb 22, comprises a base plate 23 with an outwardly extending post 24 integral therewith, the post terminating in an upwardly extending keeper hook 25, the outer surface of which is curved upwardly 50 and to the rear to provide a cam against which the roller 11 on the latch lever may ride should the lever accidentally or otherwise be moved to the position illustrated in Fig. 2 while the door is still open. A finger 26 extends from the base 23 of the keeper above the bar 24 and hook 25, and its under edge is inclined upwardly and outwardly 55 forming a cam against which the end of the lever or the roller 11 thereon engages so as

to turn the keeper engaging end of the lever downwardly as the door is closed, and cause the spring 20 to act upon the lever, after its line of force has passed across the axis of the pivot pin 16, to force the keeper engaging end of the lever into snug wedging engagement therewith. 70

In Fig. 8 a slightly different form of construction is shown with respect to the latch lever. Instead of making the seats 14 for the head 19 in the web of the lever itself, a metal plate 27 is placed against the upper side of the lever 8, the pivot 16 passing therethrough, and extends to the opening 13 in the lever, having a projection 28 which extends into said opening and provides two oppositely disposed seats or sockets 29. The material from which the plate 27 and the sockets 29 are made may be of steel so that it can be hardened to sustain wear. 85

The construction of latch is very simple and economical from a manufacturing and assembly standpoint. The parts are easily fabricated and assembled. When the door is open the latch lever will be in the position shown in either Figs. 1 or 3, depending upon whether it is a right or left hand swinging door, and the levers will be held in the position shown by the force of spring 20. On closing the door the keeper engaging end of the lever passes above the hook 25 of the keeper, strikes against the cam edge of the finger 26 and the lever is automatically turned so as to change the action of the spring 20 to cause the lever then to swing 90 so as to force the keeper engaging end of the lever into close wedging engagement with the keeper hook. The disengagement of the lever from the keeper is accomplished by grasping the handle 9 and turning the lever in a clockwise direction, in Fig. 1, or a counterclockwise direction with the construction shown in Fig. 2. 95

The head 19 on bar 18 may be readily changed from one seat 14 or 29 to the other after the latch is completely assembled, an opening through the base plate 6 being made directly at the head 19 for access thereto by a screw driver or similar tool to shift the head 19 as may be desired. 100

The claims appended hereto define the invention which is to be considered comprehensive of all forms of structure coming within their scope. 115

I claim:

1. In a latch construction, a housing, a lever extending through the housing and pivotally mounted between its ends within and adjacent one end of the housing, said lever having two seats between the pivot and the opposite end of the housing, one being located at each side of the longitudinal center line of the lever, a bar having a head located in one of said seats, said head being changeable in position to seat in the other of said seats, and 125

130

135

spring means around the bar between said head and the opposite end of the housing, for pressing the head against the seat on which it is located.

5 2. A latch construction comprising, a housing, a latch lever extending through the housing, a pivot pin carried by said housing extending through the lever adjacent one end of the housing, said lever being of channel 10 cross section and having a part of the web cut away to provide an opening in the lever between the pivot and the opposite end of the housing, seats on said lever in said opening adjacent the pivot, one of said seats being 15 located at each side of the longitudinal center line of the lever, and spring actuated means between the opposite end of the housing and said seats carried by the lever, said spring means pressing against a selected seat and 20 being shiftable to act upon either seat.

3. A latch construction comprising, a housing having a top and inwardly extending sides and ends, said ends having openings therethrough and one of said ends having the 25 material at said opening extending inwardly into and underneath the top of the housing, substantially parallel thereto, a sleeve on said last mentioned material extending between the same and the top of the housing, a lever 30 passing through the housing and through the ends thereof, a base closing the inner side of the housing, and a pivot pin passing through said base, lever and received in said sleeve.

4. A latch construction comprising a housing having an opening in opposed ends thereof, a latch lever extending through the housing and the openings in its ends, a pivot carried by the housing and passing through said latch lever near one end of the housing, said 40 latch lever within the housing being channel shape in cross section and having an opening made in the web of the channel between the pivot and the opposite end of the housing, said opening at the end adjacent the pivot being 45 equipped with two seats, one located at each side of the longitudinal center line of the lever, a bar disposed between the lever and the outer side of the housing, a head on said bar extending into the opening in the lever and bearing at its free end against one of said seats and a coiled compression spring 50 around said bar bearing against said head at one end and against said opposite end of the housing at the other end, said head being 55 shiftable from one seat to the other.

In testimony whereof I affix my signature.
EDWARD F. GRAF.
